DESIGN FOR A VANITY TABLE

Leo Jiranek, New York, N. Y., assignor to Heywood-Wakefield Company, Gardner, Mass., a corporation of Massachusetts

Application July 17, 1936, Serial No. 63,893

Term of patent 3½ years

To all whom it may concern:

Be it known, that I, Leo Jiranek, a citizen of the United States and a resident of New York, county of New York, and State of New York, have invented a new, original, and ornamental Design for a Vanity Table, of which the following is a specification, reference being had to the accompanying drawing, forming a part thereof, in which

Fig. 1 is a perspective view of a vanity table showing my new design and Fig. 2 is a fragmentary detail view on the line 2—2 of Fig. 1, but on an enlarged scale with respect to Fig. 1.

I claim:

The ornamental design for a vanity table substantially as shown.

LEO JIRANEK.
